CORE TYPE REEL DRIVE

Rest R. Baker, Pittsburgh, Pa., assignor to Westinghouse Electric Corporation, East Pittsburgh, Pa., a corporation of Pennsylvania

Application February 24, 1947, Serial No. 730,501

7 Claims. (Cl. 242—75)

1

My invention relates to electric drives for winding yarn, thread, strips, or sheets of paper, textile, metal, or other material onto or off a core-type reel.

For the operation of core-type reels, it is frequently necessary or desirable to maintain a constant tension in the material being reeled. In fabricating machinery, it is usually required to move the material to be reeled at a substantially constant linear traveling speed. In order to meet this requirement, the equipment for driving the core-type reel must necessarily vary the rotational speed of the core due to the fact that the diameter of the reeled material changes progressively during the reeling operation. To accomplish a proper variation in rotational speed, the core drives are frequently equipped with "slip-belt" drives. Such drives are designed to rotate the empty core at the correct speed and to slip the amount necessary for accommodating the larger roll diameters. In order to maintain constant tension in the material being reeled, it is also necessary to increase the torque on the core drive shaft as the roll diameter increases.

There are electric drives to replace the slip-belt type of drive for the above-mentioned purposes. These electric drives have a reel drive motor of the direct-current type whose field is separately excited by means of a current regulator. The electric drive functions to maintain, at a particular operating speed and voltage, a constant current input to the reel motor. Constant current input at constant voltage is equivalent to constant horse-power input which results in substantially constant tension in the material being reeled. As the diameter of the roll of material on the core increases, the current regulator increases the field excitation of the reel motor, and at maximum diameter of the roll, the motor has a field excitation equivalent to the ratio of maximum diameter to minimum diameter times minimum excitation. The torque developed at constant current will then be in the direct ratio of the maximum and minimum diameters, and the operating speed is then inversely proportional to the diameters.

It is an object of my invention to provide an electric drive for core-type reeling equipment which is capable of maintaining the material to be reeled under substantially constant tension, while requiring for this performance a considerably reduced amount of equipment as compared with the above-mentioned electric drives heretofore known for this purpose.

2

Another and more particular object of my invention is to provide an electric reel drive which maintains substantially constant tension in the material without requiring the use of the above-mentioned current regulators, but performs its tension-regulating function by virtue of electric characteristics inherent in the drive system proper.

In order to achieve these objects, and in accordance with one of the features of my invention, I provide a core-type reel drive with a direct-current drive motor of the series type which is so rated that it operates along the unsaturated and substantially straight portion of its magnetic characteristic; and I further provide the armature and series field circuit of this motor with electric calibrating means, such as an impedance or a source of bucking voltage, which adjusts the IR drop in this armature circuit relative to the energizing voltage impressed on a motor so that the following conditions are satisfied.

In order to maintain constant tension in the strip, at a single strip speed, the torque of the motor must vary directly as the roll diameter while the speed of the motor must vary inversely as the diameter. The speed of a series motor may be adjusted by varying the IR drop in the armature circuit. From the required relationships, given above, between torque, speed, and diameter, and from the well known speed and torque equations of an unsaturated series motor, it can be shown that the speed and torque of such a motor will vary so as to maintain constant tension provided that the IR drop in the armature circuit is so adjusted that the following equation is substantially satisfied.

$$40 \quad \frac{IR}{E} = \frac{1}{\sqrt{\frac{D_2}{D_1}} + 1}$$

wherein IR represents the IR drop in the armature circuit; E, the voltage energizing the circuit; D₂, the maximum diameter of the roll of material reeled up on the core; and D₁, the minimum diameter of that roll which is usually identical with the diameter of the reel core.

It can be seen that, by the use of the above equation, it is possible to select a single value of R that will satisfy the requirements for constant tension at two roll diameters. It has been found that a value of R so selected will cause operation at substantially constant tension over a wide variation of roll diameters.

If the fabricating machinery, that passes the material toward the reel, operates at constant speed, the energizing voltage for the drive motor is also constant, and hence may be derived from any suitable source of constant direct-current voltage. However, if the fabricating machinery associated with the reel is designed for operation at adjustable speed, then the voltage for energizing the motor must change in proportion to the change in the linear traveling speed of the material to be reeled. In order to obtain the proper variation in voltage, and in accordance with another feature of the invention, this voltage may be generated by a direct-current generator whose armature is connected to the fabricating machinery in order to rotate at a speed proportional to the traveling speed of the material.

The above-mentioned and other objects and features of my invention will be apparent from the following description of the embodiments illustrated in the drawing, in which:

Figure 1 represents diagrammatically a fabricating machine and reel drive in conjunction with the essential circuits and devices of an electric reel drive according to the invention.

Fig. 2 is an explanatory speed torque diagram relating to the electric systems shown in Figs. 1 and 3, and

Fig. 3 represents diagrammatically a modified form of drive according to the invention.

According to Figure 1, the material 1 passes through fabricating machinery 2, here schematically represented as a calender, and passes from this machinery onto the core 3 of winding equipment. The core 3 is driven by a suitable mechanical transmission 4 from the armature 5 of a direct-current series-type motor M whose series field is denoted by 6. The transmission, here shown as a shaft connection, may include the reduction gears usually present in such equipment. The motor circuit is energized from the armature 7 of a generator G whose field winding 8 is separately excited from a constant voltage source 9, preferably through a calibrating rheostat 10. The adjustment of rheostat 10 need not be changed during the normal operation of the drive system. The generator armature 7 is mechanically connected to the machinery 2 by means of a transmission 11, here schematically represented by a shaft connection. This transmission, as shown, is also in mechanical connection with a motor 12, or other prime mover, for operating the machinery 2 at the desired speed. A speed-adjusting device for the motor 12 is schematically exemplified by a rheostat 13. An adjustable rheostat 14 is connected in the motor or load circuit in series relation to the armatures 5 and 7 and the motor field winding 6. The slide contact of rheostat 14 is connected, as schematically shown at 15, with the adjustable member of the speed control device 13 so that the setting of rheostat 14 is changed together with any change in the speed adjustment of the device 13.

In the coordinate diagram shown in Fig. 2, a speed torque characteristic is denoted by 16 as being representative of the speed torque relation required for the transmission 4 in order to maintain the material 1 under constant tension for any singular traveling speed of the material 1. The required ideal speed torque curve 16 has a hyperbolic form. If, in the drive system according to Figure 1, the motor M operates within the unsaturated and approximately straight region of its magnetic characteristic, and if the

resistance value of rheostat 14 is so adjusted by the appertaining slide contact that, at the just-mentioned singular speed, the IR drop including the circuit conductors, the rheostat 14, the armatures 7 and 5 and the field winding 6 bears the relationship to the applied voltage indicated by the above-given equation, then the reel performance will closely match the speed torque requirement represented by the curve 16 in Fig. 2. That is, under the just-mentioned conditions, the actual driving effort exerted by the motor M on the transmission 4 corresponds approximately to the speed torque characteristic 17 in Fig. 2. The percentage of reeling error is very small and negligible for most cases of application, especially if the actual performance characteristic 17 is made to intersect the ideal characteristic 16 in such a manner that the remaining errors are approximately equally distributed between plus and minus values.

If the speed of the processing or fabricating machinery, and hence the linear traveling speed of the material, is changed, the voltage E impressed on the load circuit of the series motor is likewise changed and it follows from the above-given equation that then the rheostat 14 must also be adjusted in order to calibrate the IR drop in the motor generator circuit to the new value required for the increased voltage. It is preferred to effect such a recalibration automatically by the transmission between the rheostat 14 and the speed-adjusting device 13 represented in Fig. 1 at 15. Consequently, when the speed-adjusting device 13 is set for a higher running speed of the machinery 2, the rheostat 14 is simultaneously adjusted for a correspondingly increased IR drop in the armature circuit. As a result, the ratio of voltage to IR drop remains in proper relation to the reeling diameters to secure substantially constant tension in the material over the available range of traveling speeds.

The embodiment shown in Fig. 3 differs from the above-described drive system of Fig. 1, substantially by the fact that a bucking generator is used in the motor circuit in order to provide for the proper calibration of the voltage to IR drop relation in this circuit.

According to Fig. 3, the material 21 passes from fabricating machinery 22 onto the core 23 of the reel drive. The core is driven through a transmission 24 from the armature 25 of the reel motor M whose field winding 26 is connected in series with the armature 25 across the armature 27 of the generator G. The field winding 28 of generator G is excited from constant voltage mains 29 through a calibrating rheostat 30 of fixed adjustment during normal operation of the system. The generator armature 27 is mechanically connected to the machinery 22 and driven together therewith by a motor 32 whose speed is adjustable by means of a rheostat 33 or other speed-controlling device.

Series connected in the circuit of motor M, is the armature 34 of a bucking generator B. Armature 34 is driven at constant speed by an auxiliary motor 35. The field winding 36 of generator B is also series connected in the circuit of motor M so that the voltage generated in the armature 34 varies in proportion to the current flowing in the motor circuit. Field winding 36 is connected with a field rheostat 37 whose slide contact is ganged together, by a transmission shown at 38, with the speed-adjusting device 33 of the motor 32.

The voltage superimposed on the motor circuit

by the bucking generator is in opposition to the energizing voltage from the generator G and is so rated by proper adjustment of the field rheostat 37 that the IR drop in the motor circuit, including the armatures 25, 27, 34 and the field windings 26, 36, with the rheostat 37, has the above-given relation to the energizing voltage E generated across the armature 27. Under these conditions, the system according to Fig. 3 functions similar to that of Fig. 1 in maintaining the tension of the material being reeled at a substantially constant value. The system of Fig. 3, though somewhat more intricate than the one shown in Fig. 1, has the advantage that it permits introducing the energy, or part of the energy, dissipated in the rheostat 14 of Fig. 1 back into the source of the electric power supply driving the motor 35.

Systems according to my invention, as exemplified by the above-described embodiments, may be provided with customary protective devices and accessories, for instance with protective contact means which stop the drive or prevent the reel from running at excessive speed in a case of a break in the material. Such and other modifications of my invention, as well as alterations and changes in the elements composing such drive systems, will be obvious to those skilled in the art, and it should therefore be understood that the invention, as defined by the annexed claims, permits of embodiments other than those specifically illustrated and described in detail in the foregoing.

I claim as my invention:

1. A core-type reel drive for maintaining substantially constant tension in the material to be reeled, comprising a direct-current reel motor having an armature and a series field winding and being rated to operate along the substantially straight unsaturated portion of its magnetic characteristic over the range of desired speeds, circuit means for providing energizing voltage proportional to the traveling speed of the material, a load circuit connected across said circuit means and including in series-connection said armature and said field winding, and a resistor series-connected in said circuit and rated to establish in said circuit an IR drop substantially in accordance with the equation

$$\frac{IR}{E} = \frac{1}{\sqrt{\frac{D_2}{D_1}} + 1}$$

wherein IR is said IR drop, E said energizing voltage and

$$\frac{D_2}{D_1}$$

the ratio of maximum to minimum diameters of the reel to be driven by said motor.

2. A core-type reel drive for maintaining substantially constant tension in the material to be reeled, comprising a direct-current reel motor having an armature and a series field winding and being rated to operate along the substantially straight unsaturated portion of its magnetic characteristic over the range of desired speeds, circuit means for providing energizing voltage proportional to the traveling speed of the material, a load circuit connected across said circuit means and including in series-connection said armature and said field winding, and a series bucking generator connected in said circuit and having a linear relationship of its bucking voltage to the current in said circuit so as to main-

tain in said circuit an IR drop substantially in accordance with the equation

$$\frac{IR}{E} = \frac{1}{\sqrt{\frac{D_2}{D_1}} + 1}$$

wherein IR is said IR drop, E said energizing voltage and

$$\frac{D_2}{D_1}$$

the ratio of maximum to minimum diameters of the reel to be driven by said motor.

3. A core-type reel drive for maintaining substantially constant tension in the material to be reeled, comprising drive means having speed-adjusting means for controlling the linear traveling speed of the material, circuit means associated with said drive means to provide a voltage proportional to said speed, a direct-current winder motor for reeling the material having an armature and a series field winding and being rated to operate along the substantially straight unsaturated portion of its magnetic characteristic over the range of desired reeling speeds, a circuit connected to said circuit means to be energized by said voltage and including in series said armature and said field winding, an adjustable control member series-connected in said circuit and connected with said speed-adjusting means so as to be adjusted together with the latter in order to maintain the IR drop in said circuit, regardless of the setting of said speed-adjusting means, substantially in accordance with the equation

$$\frac{IR}{E} = \frac{1}{\sqrt{\frac{D_2}{D_1}} + 1}$$

wherein IR is said IR drop, E said energizing voltage and

$$\frac{D_2}{D_1}$$

the ratio of maximum to minimum diameters of the reel to be driven by said motor.

4. A core-type reel drive for maintaining substantially constant tension in the material to be reeled, comprising drive means having speed-adjusting means for controlling the linear traveling speed of the material, a generator mechanically connected to said drive means for providing a voltage proportional to said speed, a direct-current winder motor for reeling the material having an armature and a series field winding and being rated to operate along the substantially straight unsaturated portion of its magnetic characteristic over the range of desired reeling speeds, a circuit including in series-connection said generator, said armature and said field winding, an adjustable rheostat series-connected in said circuit.

5. A core-type reel drive for maintaining substantially constant tension in the material to be reeled, comprising drive means having speed-adjusting means for controlling the linear traveling speed of the material, a generator mechanically connected to said drive means for providing a voltage proportional to said speed, a direct-current winder motor for reeling the material having an armature and a series field winding and being rated to operate along the substantially straight unsaturated portion of its magnetic characteristic over the range of desired reeling speeds, a circuit including in series-connection said generator, said armature and said field wind-

ing, a bucking generator having an armature connected in said circuit in series-opposition to said first generator and having a field winding connected to said circuit so as to provide a bucking voltage proportional to the current in said circuit, an adjustable field rheostat associated with said field winding of said bucking generator and connected with said speed-adjusting means so as to be adjusted together with the latter in order to maintain the IR drop in said circuit, regardless of the setting of said speed-adjusting means, substantially in accordance with the equation

$$\frac{IR}{E} = \frac{1}{\sqrt{\frac{D_2}{D_1} + 1}}$$

wherein IR is said IR drop, E said energizing voltage and

$$\frac{D_2}{D_1}$$

the ratio of maximum to minimum diameters of the reel to be driven by said motor.

6. With fabricating machinery for material having an adjustable speed drive for said machinery, the combination of a winder drive for reeling said material comprising a direct-current generator having an armature mechanically connected to said machinery to be driven at proportional speed and having a separately excited field winding for constant excitation to provide a voltage substantially proportional to said speed, a direct-current motor having an armature and a field winding, an adjustable rheostat, a circuit including in series relation said generator armature, motor armature, motor field winding and rheostat, said rheostat having its resistance rated to adjust the IR drop in said circuit substantially in accordance with the equation

$$\frac{IR}{E} = \frac{1}{\sqrt{\frac{D_2}{D_1} + 1}}$$

wherein IR is said IR drop, E said energizing voltage and

$$\frac{D_2}{D_1}$$

the ratio of maximum to minimum diameters of the reel to be driven by said motor, and means

connecting said rheostat with said machinery drive so as to calibrate said rheostat for maintaining said equation when said machinery drive is set for a different speed.

7. With fabricating machinery for material having an adjustable speed drive for said machinery, the combination of a winder drive for reeling said material comprising a direct-current generator having an armature mechanically connected to said machinery to be driven at proportional speed and having a separately excited field winding for constant excitation to provide a voltage substantially proportional to said speed, a direct-current motor having an armature and a field winding, a circuit including in series said generator armature, said motor armature and said motor field winding, a bucking generator having an armature driven at constant speed and having a field winding connected in series with said latter armature in said circuit so that said bucking generator provides a bucking voltage substantially proportional to the current in said circuit, and an adjustable rheostat associated with said bucking generator and connected with said machinery drive to be adjusted in dependence upon the speed adjustment of said machinery drive in order to maintain in said circuit an IR drop substantially in accordance with the equation

$$\frac{IR}{E} = \frac{1}{\sqrt{\frac{D_2}{D_1} + 1}}$$

wherein IR is said IR drop, E said energizing voltage and

$$\frac{D_2}{D_1}$$

the ratio of maximum to minimum diameters of the reel to be driven by said motor.
